UNITED STATES PATENT OFFICE.

HIRAM M. BURDICK, OF UTICA, NEW YORK.

WING FOR CORN-HARVESTERS.

SPECIFICATION forming part of Letters Patent No. 733,140, dated July 7, 1903.

Application filed April 6, 1903. Serial No. 151,264. (No model.)

To all whom it may concern:

Be it known that I, HIRAM M. BURDICK, a citizen of the United States, residing at Utica, in the county of Oneida and State of New York, have invented certain new and useful Improvements in Wings for Corn-Harvesters, of which the following is a specification, reference being had therein to the accompanying drawings.

This invention relates to harvesters, and particularly to knife-guards of corn-harvesters and the like.

Among the objects of the invention are to provide simple and effective means for operating the knife-guards, to assemble such means entirely upon the wings of the machine, to provide a novel foot-treadle for moving the guard, this treadle being of such construction that it is held in the required position for exposing the knife without any exertion on the part of the operator and by the foot of the operator placed in a natural position flat on the wing, to arrange the guard-operating mechanism in such manner that it is necessary to form a relatively small number of apertures in the wing and no slotted opening therein, no strength of the wing being sacrificed by a multiplicity of rivet and other holes and slots, and to provide a housing for the studs and slots of the knife-guard which will at all times cover said studs and slots whether the guard is in an inward or outward position.

Novel details in the construction and arrangement of the several parts of the device will be apparent from the detail description hereinafter when read in connection with the accompanying drawings, forming part hereof, and the appended claims. In the said drawings a preferable embodiment of the invention is disclosed for purposes of illustration, and when referring to the same like reference characters will designate corresponding parts in the several views, of which—

Figure 1 is a view of the knife-carrying wing attached to a corn-harvester. Fig. 2 is a top view of the wing. Fig. 3 is a bottom view thereof. Fig. 4 is an end view thereof. Fig. 5 is a sectional view of the treadle, and Fig. 6 is a view of the housing for the guard-slots.

Referring more particularly to the draw-

ings, A designates a corn-harvester, to which a wing 1 is laterally hung in the usual manner by hinge members 2 and 3, suitably fastened, preferably, to the top surface of the wing. One edge of the wing slopes outwardly and rearwardly from the machine, and along this edge is fastened a knife 4. A foot-treadle 5 is provided on the wing. This treadle has a drum 6, with bearings 7 and 8, journaled in bearings at 9 and 10, formed in a bracket 11 and in the wing, respectively. The bearing or part 10 extends through the wing, and the main or larger part of drum 6 stops at and abuts the surface of the wing. The bracket 11 is fastened to the top surface of the wing 1, preferably to the hinge member 2, and a bolt 12 passes vertically through the bracket, drum, and wing. A collar 13 is formed at or near the top of the drum 6, and a foot-lever 14 extends therefrom, said lever having a flaring and somewhat-curved end 15 for convenient engagement by the foot of the operator. An arm 16, for convenience termed the "link-arm," extends from part 10 near the bottom surface of the wing. Foot-lever 14 and link-arm 16 are substantially oppositely disposed with reference to the drum 6. A coiled spring 17 is disposed around drum 6, one end of the spring engaging the projection formed by hinge member 2 and the other end engaging foot-lever 14, and the spring being held on the drum by collar 13 and the surface of the wing. The tendency of the spring is to cause the treadle to rotate. On the under surface of the wing and adjacent to the edge of the knife 4 is placed a knife-guard 18, held by studs 19 and operating thereon through slots 20. The knife-guard 18 and link-arm 16 are operatively connected by a link 21, held thereto by pivot-studs 22 and 23, respectively. Adjacent to the end of the link-arm 16 is a shoulder 24, and pivot-stud 23 is located on said link-arm at a point more removed from the end thereof than said shoulder. Spring 17 tends to cause the foot-lever 14 and link-arm 16 to swing around; but the shoulder 24, engaging link 21, stops such movement when link-arm 16 and link 21 are thrown practically as far as possible in the direction of the guard 18, and said guard is in its outward or guarding position. This is the normal position of the

guard and its attendant operating mechanism. The guard is withdrawn and the knife exposed by swinging foot-lever 14 inwardly, thus operating link-arm 16 and link 21, connected to the guard. The construction and arrangement of link 21, pivot-stud 23, and shoulder 24 relative to each other are such that the movement of said link-arm by spring 17 is stopped by said shoulder when said arm is swung around slightly beyond a straight line between drum 6 and pivot-stud 22 on the guard 18. It will thus be seen that means are provided for doubly locking guard 18 in its outward or guarding position. The guard would not only be prevented from receding upon sustaining any impact in the direction of the knife by tension of the spring 17, holding shoulder 24 against link 21, and thereby the guard in its outward position, but said link-arm and link being held beyond a straight line by said spring, as described, such an impact would tend to increase the safety of the locked position in that it would increase the pressure between said shoulder and said link.

In order to protect studs 19 and slots 20 from injury and from being fouled during operation of the machine, housings 25 are provided therefor. These housings are fastened to guard 18 in any suitable manner, as by lugs 26, engaged by screws 27, and they completely cover the slots and studs and move over the studs as the guard is moved. The housings are preferably made of metal and are of substantially dish shape, the edges thereof bearing against the guard to which they are attached.

The machine to which such wings as described hereinbefore are attached, one on each side, being in operation, the knives thereof extend to cut two rows at a time. An operator is stationed on each side of the machine to support the stalks as the knives strike them and to draw them back, so that the butts rest on the wings. To withdraw the guard and expose the knife, the foot-lever 14 is swung inwardly by the foot, thus moving the guard-operating mechanism in an obvious manner, as described, and the foot is placed flat on the wing against the raised projection formed by hinge member 2. When the foot is in this position, it is interposed between foot-lever 14 in its inward position and the raised projection, and said foot-lever is therefore held in its desired place, notwithstanding the exertion of the spring 17 to the contrary, by the shoe of the operator. When the foot is removed by reason of the desire of the operator to stop the cutting operation or should he be accidentally thrown from the machine, the spring 17 operates to swing the foot-lever back and throw out the guard and protect the knife.

Having thus described my invention, what I claim as new, and desire to secure by Letters Patent, is—

1. In a wing for corn-harvesters, a fixed

knife, a guard for said knife, a horizontally-operating treadle, and a link connecting said guard and said treadle, substantially as described.

2. In a wing for corn-harvesters, a fixed knife, a guard for said knife, a horizontally-operating treadle, a link connecting said guard and said treadle, and a spring operating to extend said guard to its outward position, substantially as described.

3. In a wing for corn-harvesters, a fixed knife, a guard for said knife, a horizontally-operating treadle, a link connecting said guard and said treadle, a spring operating to extend said guard to its outward position, and means for limiting the movement of said treadle, substantially as described.

4. In a wing for corn-harvesters, a fixed knife, a guard for said knife, a horizontally-operating treadle having a foot-lever and a link-arm, a link connecting said guard and said treadle, a spring operating to extend said guard to its outward position, and a projection on said wing for engagement by the foot of the operator when said foot-lever is swung to withdraw the guard and expose the knife, substantially as described.

5. In a wing for corn-harvesters, a fixed knife, a guard for said knife, a horizontally-operating treadle having a foot-lever and a link-arm, a link connecting said guard and said treadle, a spring operating to extend said guard to its outward position, and means for limiting the movement of said treadle, substantially as described.

6. In a wing for corn-harvesters, a fixed knife, a guard for said knife, a horizontally-operating treadle having a foot-lever and a link-arm, a link connecting said guard and said treadle, a spring operating to extend said guard to its outward position, and a shoulder on said link-arm and arranged to engage said link for limiting the movement of said treadle, substantially as described.

7. In a wing for corn-harvesters, a fixed knife, a guard for said knife, a horizontally-operating treadle having a foot-lever and a link-arm, a link connecting said guard and said treadle, a spring operating to extend said guard to its outward position, and a shoulder on said link-arm, said shoulder being arranged to engage said link and stop the movement of said treadle when said link and arm have passed beyond a straight line between the axis of said treadle and the point of connection between said link and said guard, substantially as described.

8. In a wing for corn-harvesters, a fixed knife, a guard for said knife, a link connected to said guard, and a horizontally-operating foot-treadle connected to said link and having a foot-lever formed with a flaring and curved end for engagement by the foot of the operator, substantially as described.

9. In a wing for corn-harvesters, a fixed knife, a guard for said knife, a link connected to said guard, and a horizontally-operating

treadle connected to said link and having a foot-lever operating adjacent to the upper surface of said wing and a link-arm operating adjacent to the under surface of said wing, substantially as described.

10. In a wing for corn-harvesters, a fixed knife, a guard for said knife, a link connected to said guard, and a horizontally-operating treadle connected to said link and having an upright drum, a foot-lever connected to said drum near its upper part, a spring on said drum for giving motion thereto, a link-arm connected to the lower part of said drum, and means on said link-arm for limiting the movement of said treadle, substantially as described.

11. In a wing for corn-harvesters, a fixed knife, a guard for said knife, a link connected to said guard, and a horizontally-operating treadle connected to said link and having an upright drum, a foot-lever connected to said drum near its upper part, a spring on said drum for giving motion thereto, a link-arm connected to the lower part of said drum, and a shoulder on said link-arm and arranged to engage said link for limiting the movement of said treadle, substantially as described.

12. In a wing for corn-harvesters, a fixed knife, a guard for said knife having slots therein operating on supporting-studs, a housing covering each of said slots and its complementary stud and movable with said guard, a horizontally-operating treadle having a foot-lever and a link-arm, a link connecting said guard and said treadle, a spring operating to extend said guard to its outward position, and a shoulder on said link-arm and arranged to engage said link for limiting the movement of said treadle, substantially as described.

13. In a wing for corn-harvesters, a fixed knife, a guard for said knife having slots therein operating on supporting-studs, a dish-shaped housing covering each of said slots and its complementary stud and fastened to said guard, a horizontally-operating treadle having a foot-lever and a link-arm, a link connecting said guard and said treadle, a spring operating to extend said guard to its outward position, and a shoulder on said link-arm and arranged to engage said link for limiting the movement of said treadle, substantially as described.

14. In a wing for corn-harvesters, a knife, a guard for said knife, a horizontally-operating treadle, and means connecting said guard and said treadle, substantially as described.

15. In a wing for corn-harvesters, a knife, a guard for said knife, a horizontally-operating treadle, means connecting said guard and said treadle, and means operating to extend said guard to its outward position, substantially as described.

16. In a wing for corn-harvesters, a knife, a guard for said knife, a horizontally-operating treadle, means connecting said guard and said treadle, means operating to extend said

guard to its outward position, and means for limiting the movement of said treadle, substantially as described.

17. In a wing for corn-harvesters, a knife, a guard for said knife, a horizontally-operating treadle having a foot-lever and an operating-arm, means connecting said guard and said treadle, means operating to extend said guard to its outward position, and a projection on said wing for engagement by the foot of the operator when said foot-lever is swung to withdraw the guard and expose the knife, substantially as described.

18. In a wing for corn-harvesters, a knife, a guard for said knife, a horizontally-operating treadle, means connecting said guard and said treadle, and a projection on said wing for engagement by the foot of the operator when said treadle is moved to withdraw the guard and expose the knife, substantially as described.

19. In a wing for corn-harvesters, a knife, a guard for said knife, a horizontally-operating treadle having a foot-lever and an operating-arm, means connecting said guard and said treadle, means operating to extend said guard to its outward position, and means for limiting the movement of said treadle, substantially as described.

20. In a wing for corn-harvesters, a knife, a guard for said knife, a horizontally-operating treadle having a foot-lever and an operating-arm, means connecting said guard and said treadle, means operating to extend said guard to its outward position, and a shoulder on said operating-arm and arranged to limit the movement of said treadle, substantially as described.

21. In a wing for corn-harvesters, a knife, a guard for said knife, a horizontally-operating treadle having a foot-lever and an operating-arm, means connecting said guard and said treadle, means operating to extend said guard to its outward position, and a shoulder on said operating-arm, said shoulder being arranged to engage the means connecting the treadle and the guard and stop the movement of said treadle when said connecting means and arm have passed beyond a straight line between the axis of said treadle and the point of connection between the connecting means and the guard, substantially as described.

22. In a wing for corn-harvesters, a knife, a guard for said knife, a horizontally-operating foot-treadle having a foot-lever formed with a flaring and curved end for engagement by the foot of the operator, and means connecting said guard and said treadle, substantially as described.

23. In a wing for corn-harvesters, a knife, a guard for said knife, a horizontally-operating treadle having a foot-lever operating adjacent to the upper surface of said wing and another arm operating adjacent to the under surface of said wing, and means connecting said guard and said treadle.

24. In a wing for corn-harvesters, a knife, a

guard for said knife, a horizontally-operating treadle having an upright drum, a foot-lever connected to said drum near its upper part, means on said drum for giving motion thereto, an arm connected to the lower part of said drum, and means connecting said guard and said treadle, substantially as described.

25. In a wing for corn-harvesters, a knife, a guard for said knife having slots therein operating on supporting-studs, a housing covering each of said slots and its complementary stud and movable with said guard, and means connecting said guard and an operating-treadle, substantially as described.

15 26. In a wing for corn-harvesters, a knife, a guard for said knife having slots therein op-

erating on supporting-studs, a dish-shaped housing covering each of said slots and its complementary stud and fastened to said guard, a horizontally-operating treadle, and 20 means connecting said guard and said treadle, substantially as described.

27. In a wing for corn-harvesters, and in combination with a knife-guard operating on slots therein, a housing for said slots movable 25 with said guard, substantially as described.

In testimony whereof I affix my signature in presence of two witnesses.

HIRAM M. BURDICK.
